which is novel, refined and in use, to effect the desired results and to achieve and to secure the objects and advantages herein set forth. It is the general purpose of this invention to provide a wire stop motion lever and a bracket and to provide therefor a wire stop motion lever and a bracket which is novel, refined and in use, to effect the desired results and to achieve and to secure the objects and advantages herein set forth.

UNITED STATES PATENT OFFICE

1,985,664

THREAD CLEANER

Willard T. Munson, Dunmore, Pa., assignor to Henry E. Collins and Albert B. Collins, both of Scranton, Pa., copartners doing business as Collins Supply & Equipment Co.

Application April 27, 1933, Serial No. 668,278

(Cl. 28—70)

The present invention relates to improvements in thread cleaners, and has for an object to provide an improved thread cleaner involving the use of blades between which the thread moves on its passage through the coning machine, and which blades perform a cleaning operation on the thread.

It is the primary object of the invention to provide an improved bracket and blade arrangement which will permit the blades to be reversed end for end and side for side whereby to secure a great number of variable clearances between the ground surfaces to the blades.

A further object of the invention resides in providing an improved blade and bracket arrangement in which the bracket will cooperate in a novel manner with the stop motion on the coning machine.

A still further object of the invention resides in providing an improved holding and pressure device for the blades so as to avoid any marring or destruction of the ground surfaces of such blades.

With the foregoing and other objects in view, the invention will be more fully described hereinafter, and will be more particularly pointed out in the claims appended hereto.

In the drawings, wherein like symbols refer to like or corresponding parts through the several views,

Figure 1 is a fragmentary perspective view of a coning machine having the improved thread cleaner mounted thereon.

Figure 2 is a top plan view of the improved cleaner.

Figure 3 is a perspective view showing a portion of the pressure device.

Figure 4 is an end view of the bracket and blades in relation to the stop motion.

Figure 5 is a horizontal section taken on the line 5—5 in Figure 4.

Figure 6 is a side elevation of the improved thread cleaner.

Figure 7 is a longitudinal vertical section taken on the line 7—7 in Figure 5, and

Figure 8 is a vertical section taken on the line 8—8 in Figure 6.

Referring more particularly to the drawings, in Figure 1 there is shown generally a conventional form of coning machine having the wire stop motion 10 and showing the thread 11 as passing through such machine and under the wire stop motion lever 10.

The improved bracket is located beneath and adjacent this stop motion lever 10 and is pro-

vided of a slot 24 which is slanted relative to the horizontal and which is adapted to receive the wire stop motion lever 10 and to cooperate therewith to provide a wire stop motion lever and a bracket which is novel, refined and in use, to effect the desired results and to achieve and to secure the objects and advantages herein set forth.

Referring to Figure 2, the improved bracket 12 is shown in perspective view and is provided with a slotted portion which receives the lever 10 and allows the same the necessary latitude of movement in performing its functions.

A pair of wings or horns 12 and 13 of the bracket extend upon opposite sides of the stop motion lever 10 and one of these wings 12 may be slightly higher than the companion wing 13. The wings are portions of an upstanding web 14 of the bracket which web, adjacent the wing 12, is amplified or enlarged into a boss 15 having an elongated slot 16 for adjustably receiving the bolt or screw stem 17 which carries the porcelain or other thread guide 18. Nuts 19 and 20 are threaded upon the stem 17 and engage opposite sides of the boss 15.

As shown in Figure 7, the web 14 rises vertically from an enlarged end portion 21 of the bracket which includes a plate 22 having an opening 23 to receive fastening means by which such bracket may be attached to an appropriate part of the coning machine. The enlarged body 21 of the bracket is formed with a slot 24 therethrough to receive the companion blades 25 and 26. Each blade, at both ends is formed with outwardly convergent surfaces 27 and 28 meeting in a substantial apex 29 which is shown to be centrally of the longitudinal axis of the blade although it may vary from this position if desired.

These inclined or sloping surfaces, each of which extend part way across the width of the blade, are adapted to be received against the inclined faces 30 and 31 of the abutment member 32 which extends up from the plate 22. The blades 25 and 26 are formed with ground longitudinal edges. In other words both edges of each blade are ground so that the blades may be reversed not only end for end but also side for side. The corner portions of the blades upon both faces thereof are provided with index characters as shown. That portion of each blade between the ends thereof inwardly of the offset or ground portions thereof constitutes an abutting edge which is adapted to abut against the edge of the adjacent or abutting blade, and the desired width of cleaning slot is formed by combining the offset portions of the two blades, that is, adding the indicia designating one offset portion of one blade to the indicia designating the offset portion of the other blade, it being understood that each numeral sets forth the exact offset in thousandths of an inch.

Referring to Figure 5, at one side of the blade slot 24 is a protection pressure plate 33 having side wings 34 within inturned claws 35 adapted to engage in wide slots 36 in the bracket member. An adjusting screw is represented at 37. The

slots 36 are wider than the claws 35 to permit of the plate 33 being advanced by the screw 37 tightly against the blades.

In the use of the device, the thread 11 passes upwardly between the blades 25 and 26, as shown in Figure 1, over the thread guide 18 and under the wire stop motion lever 10. The wings 12 and 13 act as a guard for the wire stop motion on the coning machine. The larger wing 12 tends to stop the wire stop lever 10 from pulling up too far. In other words, it steadies the lever 10 as the thread passes under this breakage lever 10.

The tension of the thread 11 holds the lever 10 back against this larger wing 12 on the cleaner bracket. If such wing were not provided, the thread tension would carry the stop lever 10 up farther and would cause it to vibrate considerably, thus producing an uneven tension.

The small wing 13 is for the purpose of checking the travel of the stop motion 10 when the thread is broken, and the stop motion functions to stop the spindle.

The blades, as shown in Figure 5, are adjusted to a clearance of ten thousandths (.010) as represented by the index characters 8 and 2 on the corner portions of adjacent edges of the blades through which the thread passes. The blades can be reversed side for side and end for end which gives a great many ground surfaces on the blades permitting of a great variety of clearances and variations.

The protection plate 33 is devised for the purpose of protecting the face of the cleaner blade which contacts with this plate from being marred by use of the set screw which holds the cleaner blades in a set position. In other words, the localized pressure on the end of the set screw 37 will not be directly received against the ground edge of the blade, but the set screw pressure is transmitted through the plate 33 which has a wide area of contact with the ground surface of the blade, and consequently the pressure will be distributed over this wide area without any bad effect. The bracket may be a die-casting and the plate 33 may be a steel stamping although the material and method of manufacture are relatively unimportant.

I am aware that blades have heretofore been proposed being reversible end for end but with the present arrangement where the blades may also be reversed side for side a great many additional variations in thread passage between the blades is afforded. In other words each blade has four wearing surfaces.

It is obvious that various changes and modifications may be made in the details of construction and design of the above specifically described embodiment of this invention without departing from the spirit thereof, such changes and modifications being restricted only by the scope of the following claims:—

What is claimed is:—

1. An improved thread cleaner comprising a bracket having an opening therein and slots adjacent the opening, blades having ground surfaces removably and reversibly mounted in the opening in said bracket, a pressure plate engaging the ground edge of one blade and having claws for engaging movably in said slots, and means for engaging the pressure plate to force same against the engaged blade.

2. An improved thread cleaner comprising a bracket having an opening therein and slots beside the opening, cleaning blades engaging in the opening, a pressure plate engaging the

ground edge of one of the blades over a wide surface and having wings and claws at the sides thereof, said claws playing loosely in said slots, and a set screw carried by the bracket for engaging the plate.

3. A thread cleaner comprising a bracket including a plate having means to attach same to a coning machine having a stop motion, an abutment rising up from said plate, said bracket having an enlarged portion with an opening therethrough, cleaning blades removably and reversibly fitted through said opening and against said abutment, a web rising from said enlarged portion and having a slotted boss therein, a guide having a supporting bolt extending through a slot with means to secure the same in adjustable position, and wings upstanding from said web lying at opposite sides of the stop motion.

4. As new articles of manufacture, a pair of thread cleaning blades, each blade comprising an elongated flat member having blade abutting portions on the opposite longitudinal edges thereof spaced inwardly from the ends of the blade, that portion of each blade on each edge thereof outwardly of the abutting portion being inwardly offset from the abutting portion whereby to form a cleaning slot outwardly of the abutting edges of the blades, each blade having each end so formed as to provide an inwardly convergent guide slot irrespective of whether the blades be reversed together end for end, edge for edge, or singly end for end or edge for edge.

5. As new articles of manufacture, a pair of thread cleaning blades, each blade comprising an elongated flat member having blade abutting portions on the opposite longitudinal edges thereof spaced inwardly from the ends of the blade, that portion of each blade on each edge thereof outwardly of the abutting portion being inwardly offset from the abutting portion whereby to form a cleaning slot outwardly of the abutting edges of the blades, the offset portion on one side of an abutting portion being offset to a degree different from the offset portion on the other side of the abutting portion, each blade having each end so formed as to provide an inwardly convergent guide slot irrespective of whether the blades be reversed together end for end, edge for edge, or singly end for end or edge for edge.

6. As new articles of manufacture, a pair of thread cleaning blades, each blade comprising an elongated flat member having blade abutting portions on the opposite longitudinal edges thereof spaced inwardly from the ends of the blade, that portion of each blade on each edge thereof outwardly of the abutting portion being inwardly offset from the abutting portion whereby to form a cleaning slot between the pair of blades outwardly of the abutting edges, the offset portion on one side of an abutting portion being offset to a degree different from the offset portion on the other side of the abutting portion and no two offset portions being of the same degree and each offset portion of one blade being different from the offset portions of the other blade, indicia on a face of each blade to indicate the depth of each offset portion, and each blade having each end so formed as to provide an inwardly convergent guide slot irrespective of whether the blades be reversed together end for end, edge for edge, or singly end for end or edge for edge.

7. The combination with a bracket adapted to be mounted on a coning machine of a pair of thread cleaning blades, each blade comprising an

5 elongated flat member having blade abutting portions on the opposite longitudinal edges thereof spaced inwardly from the ends of the blade, that portion of each blade on each edge thereof outwardly of the abutting portion being inwardly offset from the abutting portion whereby to form a cleaning slot between the blades

outwardly of the abutting edges of the blades, each blade having each end so formed as to provide an inwardly convergent guide slot irrespective of whether the blades be reversed together end for end, edge for edge, or singly end for end or edge for edge.
